VACUUM RESPONSIVE GOVERNING MEANS
FOR INTERNAL COMBUSTION ENGINES

Arthur F. Stern and Harvey W. Hanners, Milwaukee, Wis., assignors to Allis-Chalmers Manufacturing Company, Milwaukee, Wis., a corporation of Delaware

Application June 13, 1936, Serial No. 85,014

10 Claims. (Cl. 123—140)

This invention relates to the manner of and means for regulating and controlling the feeding of fuel to internal combustion engines and more particularly to the manner and means for controlling and regulating the fuel pumping unit in accordance with variations in vacuum in the intake manifold.

A type of fuel feeding means commonly employed, particularly in connection with engines of the Diesel or semi-Diesel type in which the fuel is injected directly into the cylinder or combustion chamber in a highly atomized state, comprises a pumping unit having a reciprocating, biased pump plunger for each engine cylinder delivering extremely small, metered quantities of fuel in timed relation to the engine cycle; the metering of the fuel in accordance with the engine requirements being accomplished by means of a vacuum responsive governing device and a positioning means operatively connected with the pump plungers or their actuating means and with the governing device to be actuated by the latter so that movement of the governor will correspondingly vary the stroke of the pump plungers.

The common practice in connection with the foregoing arrangement in order to maintain the governing mechanism in continuous and operative engagement with the pump plungers or their actuating means is to use either a relatively strong spring to bias the movable element of the governor, which is usually a piston, together with the positioning means and the associated mechanism or to bias the movable governor element by means of a relatively weak spring and to include an additional biasing means operatively associated with the positioning means or the interconnecting mechanism.

In the first instance, the use of a strong spring materially decreases the sensitiveness of the governor and renders it extremely difficult if not impractical to adjust for all operating conditions of the engine, and in the second instance in order to maintain the governor sensitive, an additional biasing means must be provided which increases the cost of manufacture and further complicates adjustment of the device.

Consequently, one of the primary objects of this invention is to provide a vacuum responsive governing mechanism which is associated with the pump plungers or their actuating means in such a manner that the aforementioned difficulties are entirely eliminated.

Another object is to associate a vacuum responsive governing device with a pump control

shaft or rod by means of a simple, direct connection which reduces friction to a minimum and is readily adjustable to control the fuel feed in accordance with the operating conditions.

Additional difficulties have been experienced with the prior art devices and arrangements in which a vacuum responsive governor is operatively associated with the fuel feeding mechanism of an engine in an attempt to maintain a constant fuel air ratio under all conditions of engine operation, due to the fact that the usual arrangements utilized a vacuum responsive piston biased by an ordinary compression spring so that the piston will move to compress the spring in accordance with the increase in vacuum in the intake manifold caused by the movement of the throttle valve towards closed position. However, with the use of an ordinary compression spring, the curve obtained by plotting piston movement against spring compression is a straight line, while the curve obtained by plotting fuel quantities as ordinates against the vacuum in the intake manifold as abscissa is substantially hyperbolic in form. Consequently, with the use of a single biasing spring, the piston movement only assimilates the fuel vacuum curve in the immediate region in which the straight line curve of piston movement is tangent to the fuel vacuum curve and although the use of two successively acting biasing springs has been used in order to obtain different rates of fuel feed for different conditions of engine operation, yet the resulting curve of piston movement, even if the springs are selected in order to make the curve of piston movement approximate the fuel vacuum curve, will only assimilate a minor portion of the fuel vacuum curve and, as a result, the device cannot be adjusted to obtain a constant fuel air ratio and satisfactory engine performance under all conditions of operation.

Therefore another primary object is to provide a vacuum responsive governing device which will so closely assimilate the substantially hyperbolic fuel vacuum curve that the corresponding and resulting fuel regulation will conform with engine requirements under all operating conditions, and a substantially constant fuel air ratio will always be maintained.

Another object is to provide a vacuum responsive governing device embodying a novel arrangement of parts which cooperate to render the device extremely sensitive, durable and cheap to manufacture.

The invention accordingly consists of the various features of construction, combinations of

elements and arrangements of parts as more particularly pointed out in the appended claims and in the detailed description, reference being had to the accompanying drawing, in which:

5 Fig. 1 is a diagrammatic elevational view of an internal combustion engine embodying the invention;

Fig. 2 is a vertical sectional view of a vacuum responsive governor taken on line II—II of 10 Fig. 3;

Fig. 3 is an elevational view of the fuel pumping means and governor with parts broken away to show the details of construction;

Fig. 4 is a fragmental sectional view of a 15 pump actuating and regulating means taken on line IV—IV of Fig. 3; and

Fig. 5 is a vertical sectional view of a modified form of governing device.

Fig. 1 illustrates a conventional internal combustion engine 1 of the Diesel or semi-Diesel type having a fuel injection pumping unit 2 delivering fuel in metered quantities through pipes 3 to the individual engine cylinders 4, an intake manifold 6 including the usual throttle valve 7, which may be actuated mechanically or by any suitable governing device not shown, an air cleaner 8 connected to the inlet end of manifold 6, and a governing device 13 operatively associated with the intake manifold by means of pipes 9 and 11 30 so as to be responsive to variations in vacuum therein and with the pump control shaft 12.

The fuel pumping device employed, reference being had to Figs. 3 and 4, comprises a casing 15 in which is positioned a plurality of plungers 14, 35 there being one for each engine cylinder, actuated on their return or intake stroke by means of springs 16 which always retains each plunger 14 in positive engagement with its tappet mechanism 17. The interior of the pump casing 15 is divided by means of a horizontal partition 18 into an upper chamber 19 into which the lower ends of the pump plungers 14 extend and a lower chamber 21 in which is positioned the pump cam shaft 22; the partition 18 having vertical bores 40 23 therein, aligned with the pump plungers and their actuating cams, in which the tappet mechanisms 17 are mounted for reciprocation. Each of the tappet mechanisms comprises a hollow piston 24 having aligned openings 26 in its side wall 50 through which the pump control shaft or pump positioning means 12 extends, an internally threaded bore 27 in the piston head receives an externally threaded stem 28 having a locking nut 31 thereon and its upper end formed to provide 55 a nut 29 for turning and adjusting the stem 28 relative to the piston 24, and trunnions 35 extending inwardly from adjacent the bottom of the piston side wall supporting a short shaft or rod 33 on which is rotatably mounted the cam 60 follower or roller 32, the roller being engaged by the high portion of the actuating cam 34 to raise the tappet mechanism and actuate the pump plunger on its injection stroke. The aligned openings 26 in the piston through which the control shaft 12 extends are of such size that the tappet mechanisms may be raised relative to the control shaft.

The control shaft 12 is mounted for rotation in bearings (not shown) formed in the end walls of 70 the pump casing 15 and has one end 36 extending into the casing 37, which houses the vacuum responsive governing device, and is provided with any suitable means 38 securing the arm 39 thereto for movement therewith, it being understood that 75 the arm 39 may be made integral with the shaft

if it is so desired. The control shaft has formed on its upper surface and in alignment with the tappet stems 28, flats 41 which are always engaged by the stems 28 when the pump plungers 14 are in their lowermost positions. Consequently, it is readily seen that rotation of the control shaft 12 will raise the tappet assembly and thus decrease or shorten the stroke of the pump plungers since the cam roller 32 will be raised relative to the actuating cam 34 and the movement imparted thereby will be decreased accordingly.

The form of vacuum responsive governing device illustrated in Fig. 2 comprises a casing 37 having formed therein a vertical cylinder 42 open 15 at its upper end; an elongated piston 44 mounted for vertical movement therein and effectively sealing said end and biased to the position shown by means of three serially arranged and co-operating springs 46, 47 and 48, the weakest 20 spring having its upper end abutting the piston head, the strongest spring 48 having its lower end abutting the bottom of the cylinder 42 and with the adjacent ends of springs 46, 47 and 47, 48 respectively abutting opposite faces of the spring 25 retainers 48 and 51; a passage formed in the outer wall of the cylinder which has a connection with the pipe 11 for subjecting the interior of the cylinder beneath the piston to the vacuum within the intake manifold; and a cover 43 provided with a connection 45 to which the pipe 9 is attached closing said open end. The piston and its biasing means are so arranged that, with substantially no vacuum effect in the intake manifold, the piston is merely floating on the springs 46, 35 47 and 48. The bottom of the cylinder has an axial bore 53 containing a sealing sleeve 54 with which is slidably mounted a stem 56 coaxing with the under side of the piston head and the underlying arm 39 on the control shaft 12 to 40 transmit the piston movement to said arm; the stem adjacent its upper end having means 57 such as a groove and washer to prevent the stem from falling out of the cylinder when the arm 39 is removed. The piston head has, in the arrangement shown, a depending boss 58, the head and boss being axially bored to receive a bolt 59 having a head 61 on its lower end against which the stem 56 abuts and the nut 62 on its upper end which coacts with the cover 43 to limit the upward movement of the piston. Obviously, instead of the bolt and nut arrangement shown, the piston could be provided with axially extended bosses directly engaging the stem and cover for the purposes above set forth or the upper boss could 55 be formed on the cover 43.

With reference to the pump control shaft 12, it is seen that the fuel feeding action of the pumping unit is greatest when the flats 41 are in a horizontal position since the tappet roller 32 is 60 always in engagement with the cam 34 and the stroke of the pump plungers is maximum, and that when the control shaft is rotated to move the flats out of their horizontal position the pumping action will be decreased, since the tappets and plungers will be raised relative to the cam 34. In this connection, it should be observed, reference being had to Figs. 3 and 4, that the shape of the actuating cams 34 is such that the pump plungers are maintained in their raised position 65 and out of engagement with the control shaft 12 throughout substantially 270° of cam rotation and it should be obvious that the time interval expressed in degrees of cam rotation during which each plunger is maintained in its raised position 70 75

will vary, assuming a single pump plunger for each engine cylinder, with the number of engine cylinders. Stated differently, the actuating means for the fuel feeding devices or pump plungers is of such a shape or nature that during the time interval existing between the reception and the delivery of a fuel charge by one of the fuel feeding devices the connection between the remaining fuel feeding devices and the control shaft or member 12 is inoperative or that the operative connection between each fuel feeding device and the control shaft or member 12 is disrupted during the time interval existing between the delivery of its fuel charge and the next delivery of a fuel charge by the precedently operated fuel feeding device. The pump plunger biasing springs 16 act through the tappet mechanisms 17, tending to rotate the control shaft 12 so as to maintain the flats 41 in a horizontal position. The control arm 39 is so positioned on the shaft 12 that with the flats in their horizontal position the stem 56 just touches or lightly engages the piston head, the arm 39 being provided with adjusting screws 63 and 64, the latter co-acting with a stop 66 formed on the governor casing 37 to determine the full load or maximum stroke of the pump plungers and the former co-acting with the piston stem 56 to eliminate any lost motion which might result from the adjustment of screw 64 or to vary the initial, relative positions of the arm and piston. The adjustment which eliminates lost motion as above pointed out enables movement of the piston to always produce a corresponding movement of arm 39 and control shaft 12 so that the fuel air ratio is maintained constant throughout the entire range of engine operation.

A boss 67 on arm 39 has connected thereto, by any suitable means, a wire or cable 68 which extends outwardly of the casing 37 for manually actuating the arm 39 downwardly to terminate the pumping action whenever the operator so desires. A cover plate 69 secured in position by any suitable means closes an opening 71 provided in the casing 37 adjacent the arm 39 in order to gain access to the adjusting screws 63 and 64.

The modified form of governing device illustrated in Fig. 5 differs from the previously described form in that the cylinder and piston are located beneath the control arm 39, thus eliminating the projection of the piston stem through the cylinder casing and the provision of a seal therefor, and in order to simplify the description corresponding parts are designated by the same reference numerals as follows: casing 37, means 38 for attaching the control arm to the shaft 12, control arm 39, vacuum cylinder 42, cover 43, springs 46, 47 and 48, spring retainers 49, 51, piston 44, piston stem 56, adjusting screws 63 and 64, stop 66, cover plate 69, and opening 71. The connection 72 for subjecting the interior of the cylinder 42 to the vacuum within the intake manifold is located in the cover 43 which closes the open, bottom end of cylinder 42 and the internally threaded axial bore in the piston top receives the externally threaded lower end 75 of the piston stem 56 which is locked against relative movement by means of nuts 73 and 74. The upper end of the stem 56 is formed with an eye or stirrup 76 loosely receiving the outer end of the control arm 39, the upper portion of this stirrup or eye mounting the adjusting screw 63 which functions in identically the same manner as does the corresponding screw in Fig. 2. In fact, the 75 operation and adjustment of this device is func-

tionally identical in all respects to the first described form.

The operation of these devices in connection with the feeding of fuel may be briefly summarized as follows: with the engine operating under full load conditions, the throttle valve 1 is fully open, the pressure in the manifold on either side of the throttle valve is substantially the same and consequently the vacuum effect in the manifold is negligible and the parts will assume the positions shown in Figs. 2 to 5 inclusive with the fuel feed a maximum. However, if the throttle valve is partially closed, the vacuum in the intake manifold will increase and, as a result, the piston 44 will move downwardly compressing one or more of the serially arranged springs 46, 47 and 48, depending upon the extent to which the throttle valve is closed, and will correspondingly move the arm 39 downwardly and rotate the control shaft 12 to raise the pump tappet mechanisms and plungers to decrease the pumping action as hereinbefore described.

The amount of rotation of the control shaft 12 necessary to decrease the rate of fuel feed from the maximum value to the minimum value corresponding to idling conditions is relatively small, being approximately 40 degrees, and consequently, in order that a sensitive governor may be used, that is, one whose movement in response to small variations in vacuum is comparatively 30 large, means reducing friction to a minimum must be provided for interconnecting the control shaft with the piston so that the piston movement is materially greater than the resultant movement of the control shaft. This result is accomplished by having the arm 39 secured to the control shaft for movement therewith, the latter directly engaging the movable element of the governing device at a material distance from the axis of said shaft.

Moreover, the use of the rotary control shaft 12 biased to a position in which the fuel pumping action is a maximum, solely by the action of the means biasing the pump plungers, enables the control arm 39 interconnecting the shaft 12 and piston stem 56 to be at all times in continuous and direct engagement therewith without additionally biasing the vacuum piston which would materially decrease its sensitivity. In addition, the foregoing arrangement eliminates the use of an additional biasing and adjusting means associated with the mechanism interconnecting the piston and control shaft which would be necessary if a sensitive governor were to be used in connection with the ordinary arrangement. The use of a relatively strong spring to bias the vacuum piston together with the associated mechanism in a continuous and direct engagement with the pump actuating means would materially decrease the sensitivity of the governor and render its adjustment impractical as it would not be free to readily respond to small variations in the vacuum.

The use of three serially arranged and successively stronger springs operating to bias the piston permits the piston movement to be relatively large in response to small variations in vacuum and to closely approximate the substantially hyperbolic fuel vacuum curve obtained by plotting fuel quantities as ordinates and vacuum in the intake manifold as abscissa. Consequently, the use of such a device will maintain the fuel air ratio substantially constant throughout the entire operating range of the engine.

The adjusting screw 63 enables the operator to readily vary the fuel air ratio in order to com- 75

5 penses for changes in the air density, such for example, as those resulting from material variations in altitude and the adjustment of screw 64 is for the purpose of making the maximum fuel 10 delivery conform with fuel characteristics and to compensate for manufacturing discrepancies. However, these two screws cooperate to enable such adjustments without subjecting the vacuum piston to any additional biasing force and without producing any lost motion in the connections between the vacuum piston and the pump actuating means.

15 It should be understood that it is not desired to limit the invention to the exact details of construction and operation herein shown and described, for various modifications within the scope of the claims may occur to persons skilled in the art.

20 It is claimed and desired to secure by Letters Patent:

1. In combination, an internal combustion engine regulator having a movable element and fuel feeding mechanism having a plurality of fuel feeding devices, means for actuating the fuel feeding devices to deliver charges of fuel in a predetermined order, biasing means acting to maintain the fuel feeding devices operatively connected with the actuating means, and a movable control member cooperating with said fuel feeding devices and with said movable regulator element and operative when moved to vary the quantity of fuel delivered by the fuel feeding devices, said actuating means and fuel feeding devices being so correlated that a single fuel feeding device biasing means acts to restrain movement of the control member in the quantity reducing direction.

2. In combination, an internal combustion engine regulator having a movable element and fuel feeding mechanism having a plurality of fuel feeding devices, means for actuating the fuel feeding devices to deliver charges of fuel in a predetermined order, biasing means acting to maintain the fuel feeding devices operatively connected with the actuating means, and a movable control member cooperating with said fuel feeding devices and with said movable regulator element and operative when moved to vary the quantity of fuel delivered by the fuel feeding devices, said actuating means being of such a nature that movement of the control member in the quantity reducing direction is at all times resisted by a single fuel feeding device biasing means.

3. In combination, an internal combustion engine regulator having a movable element and fuel feeding mechanism having a plurality of fuel feeding devices, means for actuating the fuel feeding devices to deliver charges of fuel in a predetermined order, biasing means acting to maintain the fuel feeding devices operatively connected with the actuating means, and a movable control member cooperating with said fuel feeding devices and with said movable regulator element and operative when moved to vary the quantity of fuel delivered by the fuel feeding devices, said actuating means being of such a nature that a single fuel feeding device biasing means acts to urge said control member into the position for causing the maximum rate of fuel feed.

4. In combination, an internal combustion engine regulator having a movable element and fuel feeding mechanism having a plurality of fuel feeding devices, means for actuating the fuel feeding devices to deliver charges of fuel in a predetermined order, biasing means acting to

5 maintain the fuel feeding devices operatively connected with the actuating means, and a movable control member cooperating with said fuel feeding devices and with said movable regulator element and operative when moved to change the position of the fuel feeding devices relative to the actuating means for varying the quantity of fuel delivered by each fuel feeding device, said actuating means being of such a nature that movement of the control member in the quantity reducing 10 direction is at all times resisted by a single fuel feeding device biasing means.

5. In a combination comprising an internal combustion engine regulator having a movable element, fuel feeding mechanism having a plurality of fuel feeding devices, means for actuating the fuel feeding devices to deliver charges of fuel in a predetermined order, a movable control member cooperating with the fuel feeding devices and with the movable regulator element, and biasing means acting to maintain the fuel feeding devices operatively connected with the actuating means and with the movable control member whereby movement of the control member operates to vary the quantity of fuel delivered by each fuel feeding device, the improvement which comprises employing actuating means of such a nature that during the time interval existing between the reception and the delivery of a quantity of fuel by one of the fuel feeding devices movement of the control member in the quantity reducing direction is resisted by the biasing means for the said one of the fuel feeding devices and the connections between the remaining fuel feeding devices and the control member are rendered inoperative.

6. In a combination comprising an internal combustion engine regulator having a movable element, fuel feeding mechanism having a plurality of fuel feeding devices, means for actuating the fuel feeding devices to deliver charges of fuel in a predetermined order, a movable control member cooperating with the fuel feeding devices and with the movable regulator element, and biasing means acting to maintain the fuel feeding devices operatively connected with the actuating means and with the movable control member whereby movement of the control member operates to vary the quantity of the fuel charge delivered by each fuel feeding device, the improvement which comprises employing actuating means of such a nature that movement of the control member in the quantity reducing direction is resisted by the biasing means for a single fuel feeding device and the biasing action exerted on the control member by each fuel feeding device is interrupted during the time interval existing between the delivery of its fuel charge and the next delivery of a fuel charge by the precedently operated fuel feeding device.

7. In a combination comprising an internal combustion engine regulator having a movable element, fuel feeding mechanism having a plurality of fuel feeding devices, an actuating means for each fuel feeding device, a movable control member cooperating with each of the fuel feeding devices and with the movable regulator element, and biasing means acting to maintain each of the fuel feeding devices operatively connected with its actuating means and with the movable control member whereby movement of the control member operates to change the position of each fuel feeding device relative to its actuating means to vary the quantity of the fuel charge delivered by each fuel feeding device, the improve- 75

- ment which comprises employing actuating means of such a nature that during the time interval existing between the reception and the delivery of a fuel charge by one of the fuel feeding devices movement of the control member in the quantity reducing direction is resisted by the biasing means for the said one of the fuel feeding devices and the connections between the remaining fuel feeding devices and the control member 10 are rendered inoperative.
8. In a combination comprising an internal combustion engine regulator having a movable element, fuel feeding mechanism having a plurality of fuel feeding devices, an actuating means 15 for each fuel feeding device, a movable control member cooperating with each of the fuel feeding devices and with the movable regulator element, and biasing means acting to maintain each of the fuel feeding devices operatively connected 20 with its actuating means and with the movable control member whereby movement of the control member operates to change the position of the fuel feeding devices relative to the actuating means to vary the quantity of the fuel charge 25 delivered by each fuel feeding device, the improvement which comprises employing actuating means of such a nature that movement of the control member in the quantity reducing direction is resisted by the biasing means for a single 30 fuel feeding device and the biasing action exerted on the control member by each fuel feeding device is interrupted during the time interval existing between the delivery of its fuel charge and the next delivery of a fuel charge by the 35 precedently operated fuel feeding device.
9. In a combination comprising an internal combustion engine regulator having a movable element, fuel feeding mechanism having a fuel feeding device for each engine cylinder, a cam 40 for actuating each fuel feeding device, a movable control member cooperating with each of the fuel feeding devices and with the movable regulator element, and biasing means acting to maintain each of the fuel feeding devices in engagement 45 with its actuating cam and with the movable control member whereby movement of the control member operates to change the position of each fuel feeding device relative to its actuating means to vary the quantity of the fuel charge delivered by each fuel feeding device, the improvement which comprises employing actuating cams of such shape that during the time interval existing between the reception and the delivery of a fuel charge by one of the fuel feeding devices movement of the control member in the quantity reducing direction is resisted by the biasing means for the said one of the fuel feeding devices and the remaining fuel feeding devices are maintained out of engagement with the control member.
10. In a combination comprising an internal combustion engine regulator having a movable element, fuel feeding mechanism having a fuel feeding device for each engine cylinder, a cam 20 for actuating each fuel feeding device, a movable control member cooperating with each of the fuel feeding devices and with the movable regulator element, and biasing means acting to maintain each of the fuel feeding devices in engagement with its actuating cam and with the movable control member whereby movement of the control member operates to change the position of the fuel feeding devices relative to the actuating means to vary the quantity of the fuel charge delivered by the fuel feeding devices, the improvement which comprises employing actuating cams of such shape that movement of the control member in the quantity reducing direction is resisted by the biasing means for a single fuel feeding device and the biasing action exerted on the control member by each fuel feeding device is interrupted during the time interval existing between the delivery of its fuel charge and the next delivery of a fuel charge by the precedently operated fuel feeding device.
